His Attorney.

UNITED STATES PATENT OFFICE.

LESLIE A. KEMPTON, OF BRIDGEPORT, CONNECTICUT, ASSIGNOR TO GENERAL ELECTRIC COMPANY, A CORPORATION OF NEW YORK.

ELECTRIC HEATING SYSTEM.

Application filed November 17, 1927. Serial No. 233,968.

My invention relates to electric heating systems, more particularly to three-wire electric heating systems, and has for its object the provision of simple and reliable means for making the electrical connections for various rates of heat generation.

My invention relates more especially to electric heating systems in which a three-wire supply source is used having twice the

10 voltage between the two outside wires as between each outside wire and the middle or neutral wire, for example, 220 volts between the two outside wires and 110 volts between each outside wire and the neutral.

15 In the operation of electrical apparatus on a three-wire circuit of this character, it is desirable to connect the load across the two outside wires as far as possible so as to balance the load on the circuit. In apparatus

20 in which a plurality of heats are provided, i. e., a plurality of different rates of heat generation, the connections may be arranged so that the heating resistor is connected across the two outside

25 wires to give the high heat, whereas the lower heat or heats may be obtained by connecting the resistor to one side only of the supply source. In making the connections for three heats, for example, i. e., high, me-

30 dium and low heats, the heating resistor may be divided into sections whereby one or both of the sections may be utilized. For high heat the two sections may be connected in series across the two outside wires, for me-

35 dium heat one section may be connected across one outside wire and neutral, and for low heat the two sections may be connected in series across one outside wire and neutral.

40 In accordance with my invention I provide simple and reliable means for carrying out the aforesaid connections for the three heats comprising two suitable rotatable contact members which are operated together and arranged to cooperate with suitable stationary contacts. The stationary contacts are electrically connected to the heating resistor and to the three electrical supply wires.

For a more complete understanding of my 50 invention reference should be had to the accompanying drawing in which Fig. 1 is a sectional view of means for carrying out the various connections in accordance with my invention; Fig. 2 is a fragmentary plan view of the device shown in Fig. 1; Fig. 3 is a

sectional view taken along the line 3—3 of Fig. 1 looking in the direction of the arrows; Fig. 4 is a fragmentary perspective view showing details of construction; Figs. 5-8 inclusive are diagrammatic representations 60 of the various connections effected by the switching means; while Fig. 9 is a diagrammatic view showing a modified form of my invention.

Referring to the drawing, in carrying out 65 my invention in one form I provide a specially constructed snap switch comprising a base plate 10 made of suitable electrically insulating material, which may be molded, such as a phenolic condensation product. 70 This base is circular in form and has a tubular metallic member 11 embedded in it and extending centrally through it, this member forming a bearing for an operating shaft 12 carrying two electrical contact members 13 75 and 14 which are rotatably mounted on the shaft in electrically insulating relation with respect to the shaft and with respect to each other. As shown, the rotatable contacts 13 and 14 are mounted on polygonal electrically 80 insulating blocks 15 and 16, the contact members being provided with polygonal apertures which fit on the blocks. The blocks are in turn secured to a polygonal metallic hub 17 provided with a central bore in which 85 the shaft 12 is free to turn. Barrier discs 18 made of insulating material are provided on each side and between the contact members 13 and 14.

A suitable driving connection is provided 90 between the shaft 12 and the hub 17 whereby the hub is turned with a snap action from one position to another. As shown a metal plate 11^a is embedded in the base 10 and further secured to the base by riveting the journal member 11 on to it. This plate 11^a is provided with four projections 19 which are equally spaced around the axis of the shaft 12 and act as stops to define four positions of the members 13 and 14. A specially 95 shaped pawl 20 is provided having a portion which fits between a pair of projections 19 and provided also with a bore in which fits an eccentric cam member 21 secured to the shaft 12. This pawl 20 has a projection 105 22 at its end which fits in a radial slot in a metallic member 23 (see Fig. 4) and this member 23 is in turn rigidly secured to the hub 17, for example, by riveting it to the hub and by providing projections on the 110

member 23 which fit in slots in a metallic member 24 provided with an octagonal bore fitting on the hub. A spiral spring 25 is also provided surrounding shaft 12 and having its ends bent laterally so as to terminate in two parallel portions 26 and 27. These portions embrace two projections 28 and 29 which are secured to the shaft 12 and the hub 17 respectively.

- 10 As thus arranged, it will be observed that when the shaft 12 is turned by knob 12^a in either direction, the spring is compressed by the engagement of the projection 28 with it and a force thereby applied to the hub 17 through the agency of the projection 27. At the same time the pawl 20 is withdrawn from between the projections 19 by the turning of the cam 21, and when the shaft 12 has been turned approximately 90° the pawl will 15 be withdrawn sufficiently to clear the projection 19 against which it is pressed by the spring, and it will then snap into the space between the next two projections 19. In this manner the contact members 13 and 14 20 are snapped from one position to another.

The contact member 13 is provided with a relatively long radial contacting projection or arm 13^a (Fig. 5), a relatively short projection 13^b situated diametrically opposite the projection 13^a, and with a shorter radial contact projection 13^c at right angles thereto. The contact member 14 is provided with a single relatively long radial contact projection 14^a and with two shorter projections 14^b and 14^c at right angles to projection 14^a and diametrically opposite each other. The two members 13 and 14 are secured to the hub 17 so as to rotate in parallel planes but with a 90° displacement, i. e., with the contact projection 13^c extending at right angles with the projection 14^a, as shown in Fig. 5.

Sets of stationary contacts 30, 31, 32, and 33 (Fig. 2) are secured to the base member in position to be engaged by the members 13 and 14 in their four positions, these stationary contacts being equally spaced at 90° angles on the base. The set 30 comprises an upper short contact 30^a and a lower long contact 30^b, the set 31 comprises a single short 45 upper contact, while the set 32 comprises an upper long contact 32^a and a lower long contact 32^b. The set 33 comprises an upper long contact 33^a and a lower short contact 33^b. It will be understood that the lower 50 stationary contacts are engaged by the rotatable contact member 13, while the upper stationary contacts are engaged by the contact member 14, the short stationary contacts being engaged by the long rotatable contact 55 projections, and vice versa. In the sets 30 and 32 the contacts are electrically insulated from each other, but the two contacts of the set 33 are electrically connected together. Suitable binding screws 34 are provided 60 whereby electrical connections may be made

with the various stationary contacts. The stationary contacts may also be considered as being arranged in two groups with which the members 13 and 14 cooperate respectively; member 13 cooperating with a group comprising the three stationary contacts 30^b, 32^b and 33^b and member 14 cooperating with a group comprising the four stationary contacts 30^a, 31, 32^a and 33^a.

Referring to Figs. 5-8 inclusive, the electric heating resistor, which, for example, may be a hot plate or oven heating unit of an electric range, is provided with an intermediate connection point or tap 35 whereby it is divided into sections 36 and 37. As shown the tap 35 is in the center so that the sections 36 and 37 have equal resistances, although obviously the tap may be at some other point whereby the sections are of unequal resistances, if desired. The central point 35 is electrically connected to the contact 31, one of the outside terminals, as shown the outside terminal of section 36, is connected to the contact 32^b, while the other outside terminal is connected to the stationary contacts 33^a and 33^b. The neutral wire of the three-wire supply source 38, shown as the middle wire, is connected to the stationary contact 32^a, while the two outside wires are connected respectively to the stationary contacts 30^a and 30^b.

With the connections previously described, when the switch is turned to the position shown in Fig. 5, i. e., the members 13 and 14 turned to the positions indicated, the heating resistor is disconnected from the supply source, this position being the "off" position. For high heat, i. e. highest rate of heat generation, the switch is turned to the next position in a clockwise direction which is shown in Fig. 6, whereby it will be observed that the two ends of the resistor are connected through the two switch members 13 and 14, respectively, to the outside wires of the supply source. This connects the two sections of the resistor in series across the higher voltage wires of the supply source, no connection with the central tap 35 being provided. For medium heat the switch is turned in a clockwise direction to the next position, as indicated in Fig. 7, whereby the central tap 35 is connected through the switch member 14 to the neutral wire, and the outside terminal of the section 37 is connected through the switch member 13 to one of the outside wires of the supply source. This connects the section 37 across one side of the supply source, the section 36 being deenergized. For low heat the switch is turned in a clockwise direction to its next position in which one end of the resistor is connected through the switch member 13 to one outside wire and the other end of the resistor is connected through the switch member 14 to the neutral wire. This connec-

tion puts the two sections in series across one side of the supply source.

It should be noted that the rotating contact member 13 serves the purpose of connecting one end of the resistor to one of the outside wires in all three of the operating positions. The same end of the resistor is connected in the high and low heat connections, while for the medium heat connection 10 the opposite end of the resistor is connected. The rotary contact member 14 serves the purpose of making the connections for the remaining outside wire and the neutral wire. For high heat it will be observed that this 15 contact member connects one end of the resistor to one outside wire, for medium heat it connects the central point to the neutral wire, and for low heat it connects one end of the resistor to the neutral wire.

20 In the modified form of my invention shown in Fig. 9, the electrical connection between the contact 33^b and the contact 33^a is eliminated and in place thereof a connection is provided between the contact 33^b and the contact 32^b. With this arrangement the connections for the resistor are the same as previously described in connection with Figs. 5 to 8 inclusive, with the exception that 25 on the medium heat connection shown in Fig. 7, the reverse end of the resistor as compared with Fig. 7 is connected to one outside wire. This energizes section 36 of the resistor instead of section 37, as shown in Fig. 7. This will be understood with reference to Fig. 7. In other words, with the 30 connections shown in Fig. 9 the switch blade 13 connects the same end of the resistor to the same outside wire for all three heats, this end of the resistor being that end which is 35 shown connected by the switch blade 13 in Figs. 6 and 8.

While I have described my invention as embodied in concrete form and as operating in a specific manner in accordance with 40 the provisions of the patent statutes, it should be understood that I do not limit my invention thereto since various modifications thereof will suggest themselves to those skilled in the art without departing from the 45 spirit of my invention, the scope of which is set forth in the annexed claims.

What I claim as new and desire to secure by Letters Patent of the United States, is:

1. The combination with a heating resistor 50 provided with an intermediate connection point, of a supply source provided with two outside wires and a neutral wire, a switching member for connecting one end of said resistor to one of said outside wires in any one 55 of three positions, and a second switching member for controlling the connections from said intermediate point and one end of said resistor to said neutral wire and one of said outside wires in three positions so as to give 60 three different rates of heat generation.

2. The combination with a heating resistor 65 provided with an intermediate connection point, of a supply source provided with two outside wires and a neutral wire, a switching member for connecting one end of said resistor to one of said outside wires in any one of three positions, a second switching member for controlling the connections from the other end of said resistor and said intermediate point to the other outside wire and said 70 neutral wire in said three positions so as to give three different rates of heat generation, and means for operating said switching members simultaneously.

3. The combination with a heating resistor 75 provided with an intermediate connection point, of a supply source provided with two outside wires and a neutral wire, a rotary switching member for connecting one end of said resistor to one of said outside wires in 80 any one of three positions, a second switching member for controlling the connections from said intermediate point and one end of said resistor to said neutral wire and one of said outside wires in said three positions so as to give three different rates of heat generation, and means for operating said switching member simultaneously from one position to another.

4. The combination with a heating resistor 85 provided with an intermediate connection point, of a supply source provided with two outside wires and a neutral wire, two rotary switching members, electrical connections whereby one of said switching members connects one end of said resistor to an outside wire in any one of three positions, and electrical connections whereby the other switching member connects one end of said resistor to the other outside wire in one position, said intermediate point to said neutral wire in a second position, and one end of said resistor to said neutral point in a third position.

5. The combination with a heating resistor 90 provided with an intermediate connection point, of a supply source provided with two outside wires and a neutral wire, switching means for controlling the connections of said resistor to such supply source comprising a 95 group of three stationary contacts connected respectively to the two ends of said resistor and one of said outside wires, a rotary contact member 100 cooperating with said stationary contacts in any one of three positions so as to connect one end of said resistor to said outside wire, a second group of four stationary contacts connected, respectively, to said intermediate point, one end of said resistor, 105 said neutral wire, and the remaining outside wire, a second rotary contact member arranged to cooperate with said second group of stationary contacts in any one of three positions so as to connect one end of said resistor to one outside wire for high 110

115

120

125

130

heat, said intermediate point to said neutral wire for medium heat, and one end of said resistor to said neutral point for low heat, and means for operating said rotary contact members simultaneously.

6. The combination with a heating resistor provided with an intermediate connection point, of a three wire source of power supply, switching means for controlling the connection between said resistor and said power supply comprising a group of three stationary contacts and a second group of four stationary contacts, two rotary members each provided with three contacts having an angular arrangement corresponding to the angular spacing of said stationary contacts, electrical connections between the ends of said resistor and two contacts in said first group respectively, an electrical connection between the third contact of said first group and an outside wire of said supply source, electrical connections respectively between two of the stationary contacts in said second group and said intermediate point and the neutral wire of said supply

source, an electrical connection between one end of said resistor and another stationary contact in said second group, and an electrical connection between the fourth contact in said second group and the remaining outside supply wire, and means for operating said rotary contact members simultaneously to various positions to give various heats, whereby for high heat the ends of said resistor are connected to the outside wires of said supply source by said rotary contacts, respectively, for medium heat one end of said resistor is connected to one outside wire by said first rotary contact and said intermediate point is connected to the neutral wire by said second rotary contact, and for low heat one end of said resistor is connected to one of said outside wires by said first rotary contact and the other end of said resistor is connected to said neutral wire by said second rotary contact.

In witness whereof, I have hereunto set my hand this 12th day of November, 1927.

LESLIE A. KEMPTON.
